(57) **CLAIM**

The ornamental design for a portable, modular coffee grinder, as shown and described.

DESCRIPTION

FIG. 1 is a perspective view of an embodiment of a portable, modular coffee grinder.

FIG. 2 is a front-side view of the portable, modular coffee grinder of FIG. 1.

FIG. 3 is a rear-side view of the portable, modular coffee grinder of FIG. 1.

FIG. 4 is a left-side view of the portable, modular coffee grinder of FIG. 1.

FIG. 5 is a right-side view of the portable, modular coffee grinder of FIG. 1.

FIG. 6 is a top view of the portable, modular coffee grinder of FIG. 1.

FIG. 7 is a bottom view of the portable, modular coffee grinder of FIG. 1.

FIG. 8 is a bottom, perspective view of an embodiment of the portable, modular coffee grinder of FIG. 1.

FIG. 9 is a perspective view of a second embodiment of a portable, modular coffee grinder of FIG. 1.

FIG. 10 is a front-side view of the portable, modular coffee grinder of FIG. 9.

FIG. 11 is a rear-side view of the portable, modular coffee grinder of FIG. 9.

FIG. 12 is a left-side view of the portable, modular coffee grinder of FIG. 9.

FIG. 13 is a right-side view of the portable, modular coffee grinder of FIG. 9.

FIG. 14 is a top view of the portable, modular coffee grinder of FIG. 9.

FIG. 15 is a bottom view of the portable, modular coffee grinder of FIG. 9; and,

FIG. 16 is a bottom, perspective view of an embodiment of the portable, modular coffee grinder of FIG. 9.

The features shown in broken lines in FIGS. 1-8 are not shown in FIGS. 9-16, respectively.

The broken lines disclosing the environment related to the claimed design are for illustrative purposes only, and form no part of the claimed design. The broken lines also obscure certain features in some views.

1 Claim, 16 Drawing Sheets
